UNITED STATES PATENT OFFICE.

HARVEY F. MARANVILLE, OF AKRON, OHIO, ASSIGNOR TO THE PERFECTION SPRING COMPANY, OF CLEVELAND, OHIO, A CORPORATION OF OHIO.

LUBRICATION SYSTEM.

1,083,332.

Specification of Letters Patent.

Patented Jan. 6, 1914.

Application filed June 29, 1910. Serial No. 569,460.

To all whom it may concern:

Be it known that I, HARVEY F. MARANVILLE, a citizen of the United States, residing at Akron, in the county of Summit and State of Ohio, have invented a certain new and useful Improvement in Lubricating Systems, of which the following is a full, clear, and exact description, reference being had to the accompanying drawings.

This invention relates to lubricating systems of the type shown in my application #545,742, filed February 24, 1910, and, while applicable in some of its features to various systems of machinery, the embodiment shown herein is designed with special reference to automobiles. By this construction, a system is provided whereby the various parts of the engine of an automobile may be conveniently lubricated, and an adjustable predetermined level of oil may be maintained in the engine base, or crank case, sediment may be automatically and conveniently removed from such base, and the surplus oil flowing from such base may be effectively filtered, washed and cooled, the construction assuming the form of an attachment, which may be applied to existing types of engine bases or crankcases by the mere substitution of a special base section or attachment for that usually provided.

Still further and generally speaking, the invention may be defined as consisting of the combinations of elements and parts embodied in the claims hereto annexed and illustrated in the drawings forming part hereof, wherein

Figure 1 represents a side elevation of a multi-cylinder engine having my invention applied thereto, Fig. 2 a vertical sectional view taken through the lower portion of a crank case, or engine base, showing a part of my invention applied thereto, and Fig. 3 a sectional detail corresponding substantially to the line 3—3 of Fig. 2.

Describing the parts by reference characters, wherein the same numerals designate like parts in the different views, 1 denotes the hood of an automobile, 2 the dash board, and 3 a front wheel thereof. Beneath the hood and supported by the frame in the ordinary manner is the engine, shown herein as of the four-cylinder type, the cylinders being designated by the numeral 4. The cylinders are supported by a base comprising an upper section or member 5 and

a lower section or member 6. The upper member may be of any ordinary or standard type, and is shown as provided with flanges or abutments 7 to which the lower member may be secured by means of corresponding flanges 8, 8^a and screw bolts 9, the two members together forming a crankcase. Each cylinder will be provided with a suitable piston between which and the crank 10 extends a connecting rod 11.

The lower section 6 is provided with a sediment chamber 12 depending therefrom and preferably cast therewith, the sediment chamber communicating with the rounded portion of the base section 6 thereabove by means of vertical connections 13 having passageways. These passageways provide somewhat elongated mouths or ports in the bottom of the casing proper. One internal side of each port is located in a vertical line extending through the center of the connecting rod and the crank center when the latter and the connecting rod are in a straight line or "on dead center." This side 14, with the curved form of base section 6, is at the lowest portion of such section. The opposite side 15 is necessarily somewhat elevated with respect to 14. Assuming that the crank shaft is driven in the direction of the arrow on Fig. 2 when the engine is going ahead, the action of each crank on the shaft is to sweep the sediment down the side of the casing in proximity to which it descends and into the connection 13, this action being greatly facilitated by the port construction just described, whereby any sediment that may tend to be carried across the port will be intercepted by the side 15 and deflected downwardly into the sediment chamber 12. Four vertical connections 13 are provided, one for each crank, and the casing section 6 will preferably be provided with transverse partitions 16, whereby said section will be divided into compartments, one for each crank, and each compartment will retain therein a sufficient quantity of oil for the immersion of the crank on its down stroke even though the engine is tipped, as for instance, when the vehicle ascends or descends a hill.

To lubricate by the "splash" system, as well as to facilitate the sweeping out of the sediment by the rotation of the crank shaft 10, each crank will be provided with a dipper or spoon, preferably a hollow curved projec-

tion 17, the projection being curved downwardly in the direction of rotation of the shaft when driving ahead.

The bottom of the sediment chamber 12 pitches downwardly, preferably from rear to front, and the chamber is provided with a clean-out plug 18 located just above the bottom, at the front or lowest end of the chamber.

10 Conveniently cast with the flange 8^a is a receptacle 19 provided with a filling tube 20, the upper end of which is substantially on a level with the top of the receptacle. This receptacle is placed in communication 15 with the sediment chamber 12 by pipe sections 21 and 22 connected by an elbow 23, the section 21 extending outwardly or laterally from the sediment chamber 12 from a point near the front and lower end thereof and above the bottom of the sediment receptacle. The pipe section 22 projects upwardly within the receptacle 19 and has its upper end threaded, as shown at 24, and to this threaded end there is applied a cup 25, 25 the cup being threaded onto the upper end of the pipe section. The receptacle 19 is provided with a cover 26.

27 denotes a pipe extending from near the bottom of the receptacle 19 to a pump 28, which may be of any ordinary construction, the shaft of the pump being indicated at 29 and being driven in any convenient manner from the engine shaft. The shaft is shown as extending into a casing 30 in which an 35 engine-driven gear may be located, arranged to mesh with a suitable gear on the shaft 29. From the pump 28 a pipe 31 extends to a filtering, washing and cooling tank 32, provided with a suitable gage 33 by means of which the level of oil in said tank may be observed. From this tank there extends a pipe 34 from which project suitable branches 35, arranged to discharge oil into the crank case or engine base in position to strike the 40 ascending cranks.

45 The operation of the apparatus will be clear from the drawing and foregoing description.

The oil to be used in the system or apparatus is inserted into the receptacle 19 through the filling tube 20, the receptacle being filled as high as the top of the cup 25. The oil in this receptacle, whether first admitted thereto or overflowing from the crank case 50 and cup 25 is pumped into the tank 32, where it is washed, purified and cooled. From this tank it flows through the header pipe 34 and branches 35, into the engine case. The revolution of the cranks, together 55 with the projections 17, effectively sweeps any heavy sediment, that may tend to accumulate in the bottom of the tank, into the receptacle 12, from which the sediment may be drawn from time to time by the removal 60 of plug 18. The oil will flow from the 65

receptacle 12, through the pipe sections 21 and 22 and cup 25 into receptacle 19, whence it will be pumped into the filter. It will be apparent that the cup 25 will determine the level of oil in the crank case or engine base 70 and that, by the adjustment of said cup, the level of the oil in the crank case may be varied as desired.

It will be observed that the oil discharged through the pipes 35 will strike on the upper side of the connecting rod bearings 11^a 75 as the cranks approach their upper centers. Part of the oil thus discharged will be thrown by the centrifugal action into the lower end of the cylinder above each crank, lubricating the inner wall thereof and another portion of the oil thus discharged will be thrown as high as the wrist pin in each piston and will lubricate the same.

In the specification and claims, reference 80 is made to the crank having a projection (17). By the term "crank," I do not propose to be limited to any special part of the crank shaft or the coöperating portion of the connecting rod, it being sufficient for the 85 purpose of my invention that any of the parts rotating with the crank shaft be provided with such a projection which can dip into the oil for the purpose of lubricating by the splash system and at the same time assist 90 in sweeping out the sediment.

Having thus described my invention, what I claim is:

1. The combination, with an engine crank case, of a receptacle communicating with 100 said case and having adjustable means for maintaining the level of oil in said case, a sediment receptacle operatively interposed between the crank case and the former receptacle, a filtering apparatus, means for supplying oil from the first mentioned receptacle to said apparatus, and supply connections extending between said apparatus and the crank case.

2. The combination, with an engine crank case, of a receptacle communicating with 110 said case and having adjustable means for maintaining a level of oil in said case, a sediment receptacle operatively interposed between the former receptacle and the case, 115 a filter, means for supplying oil from the first-mentioned receptacle to the filter, and supply connections extending between the filter and the crank case.

3. The combination, with a crank case, of a 120 crank in said case, said case being provided with a port in the bottom thereof beneath said crank, a sediment receptacle communicating with said port, and a second receptacle communicating with the first mentioned 125 receptacle and having adjustable means for maintaining a level of oil in said case extending above said port.

4. The combination of a crank case, said case comprising an upper and a lower sec- 130

tion detachably connected, the lower section being provided with a plurality of elongated ports in the bottom thereof and a sediment receptacle beneath said ports and communicating, thereby with the crank case, said sediment receptacle having an inclined bottom and provided near the lower end with a clean-out opening, a receptacle cast with said lower section, and a duct connecting

10 the latter receptacle with the lower portion of the sediment receptacle above the bottom thereof, the latter receptacle being provided with a filling connection and having means for maintaining a level of oil in the crank 15 case.

5. The combination of a crank case, said case comprising an upper and a lower section detachably connected, the lower section being provided with a plurality of 20 ports in the bottom thereof and a sediment receptacle beneath said ports and communicating thereby with the crank case, said sediment receptacle having an inclined bottom and provided near the lower end with 25 a clean-out opening, a second receptacle carried by said lower section, and a pipe connecting said receptacles and extending above the bottom of the second receptacle, the latter receptacle being provided with a filling 30 connection and having a cup adjustably mounted on said pipe for maintaining a level of oil in the crank case.

6. The combination, with a crank case having an aperture in the lower portion 35 thereof, of a crank in said case above said aperture, a receptacle communicating with said case through said aperture and having adjustable means for maintaining a level of oil in the case above said aperture, a sediment receptacle operatively interposed between said case and the former receptacle, a filter, means for supplying oil from the first mentioned receptacle to the filter, and connections between said filter and the crank 45 case.

7. The combination, with a crank case having an aperture in the lower portion thereof, of a crank in said case above said aperture, a receptacle communicating with 50 said case and having adjustable means for maintaining a level of oil in the case above said aperture, a sediment receptacle communicating with said aperture, a filter, means for supplying oil from the first mentioned receptacle to the filter, and connections between said filter and the crank case.

8. The combination, with a crank case having a crank therein and provided in its bottom with an elongated port or aperture, a 55 one side of which is at substantially the lowest point of the case and the other side of which is at a point above the former side, a sediment receptacle communicating with the case through said port or aperture, a crank in said case above said port or aperture,

ture, a downwardly curved projection carried by said crank, and means for maintaining a level of oil in said case above said port.

9. The combination, with a crank case 70 having a crank therein and provided in its bottom with a port or aperture, a sediment receptacle communicating with the case through said port or aperture, a crank in said case above said port or aperture, a 75 downwardly curved projection carried by said crank, and means for maintaining a level of oil in said case above said port or aperture.

10. The combination, with a crank case 80 having an aperture in the lower part thereof of one side of which is at substantially the lowest point of the case and the other side of which is located above the former side, of a sediment receptacle below said case and 85 communicating therewith through said aperture, a receptacle located above the sediment receptacle, a pipe extending from a point above the bottom of the sediment receptacle and connecting the same with the latter receptacle, adjustable means in the latter receptacle for maintaining a level of oil in the crank case, a filter, means for supplying oil from the second receptacle to said filter, and an oil supply connection leading from the 90 filter to the case.

11. The combination of a crank case having a detachable bottom section, said section being provided with a sediment receptacle located therebeneath and communicating therewith by a plurality of ports, the sediment receptacle being provided with a downwardly inclined bottom and a clean-out opening above the lower end thereof, a second receptacle carried by said bottom section above the sediment receptacle and having means for maintaining a level of oil 100 above the apertures in said bottom section, means connecting the former receptacle with the latter receptacle, a filter, means for forcing oil from the second receptacle to the filter, and connections for supplying oil from 105 said filter to the crank case.

12. A detachable base member for crank cases comprising a section provided with 115 attaching means for securing it to the upper section of the crank case, said lower section being provided with a lateral flange, a receptacle carried by said flange having means for maintaining a level of oil in the crank case, a 120 sediment receptacle projecting from the lower section and communicating with such section, and a connection between the two receptacles.

13. The combination, with a crank case 125 having an aperture in the lower part thereof, of a sediment receptacle below said case and communicating therewith through said aperture, a second receptacle, a pipe extending from a point above the bottom of the 130

sediment receptacle and connecting the same with the latter receptacle, a cup adjustably mounted on said pipe in the latter receptacle for maintaining the level of oil in the crank case, a filter, means for supplying oil from the second receptacle to said filter, and an oil supply connection leading from the filter to the case.

14. The combination, with a crank case having a plurality of transverse partitions dividing it into compartments, of a crank for each compartment, a sediment receptacle below said case, said case being provided at the bottom of each compartment with an elongated, port adapted to discharge into the sediment receptacle, one side of each port being located at substantially the bottom of the compartment and the other side being located above the former side, and a second receptacle located above the sediment receptacle and communicating therewith and having adjustable means for maintaining a level of oil in the crank case.

15. The combination, with a crank case having a plurality of transverse partitions dividing it into compartments, of a crank

for each compartment, a sediment receptacle below said case, said case being provided at the bottom of each compartment with a port adapted to discharge into the sediment receptacle, and a second receptacle located above the sediment receptacle and communicating therewith and having adjustable means for maintaining a level of oil in the crank case above the cranks when the latter are on their lower centers.

16. The combination of a crank case provided in its bottom with a port or aperture, a sediment receptacle communicating with the case through said port or aperture, a crank in said case above said port or aperture, a projection carried by said crank, and means for maintaining a level of oil in said case above said port or aperture and at a sufficient height for said projection to dip into.

In testimony whereof, I hereunto affix my signature in the presence of two witnesses.

HARVEY F. MARANVILLE.
